UNITED STATES PATENT OFFICE

NELSON K. SMITH, OF LOS ANGELES, CALIFORNIA, ASSIGNOR TO BYRON JACKSON CO.,
OF WEST BERKELEY, CALIFORNIA, A CORPORATION OF DELAWARE

TONGS

Application filed December 3, 1927, Serial No. 237,509. Renewed June 12, 1931.

This invention relates to tongs, and is more particularly related to tongs which are adapted for use in the making up and breaking of strings of casing, drill pipe, and the like, used in the construction or drilling of oil or like wells.

Casing tongs have heretofore been provided for the making up and breaking of strings of casing and drill stems but each 10 size of pipe casing and pipe collar has required a tong specially built as to size in order to handle the same or the tongs have been provided with removable jaws enabling the same to be used upon pipes or 15 their pipe collars which are of larger exterior diameters than the pipe with which said collars are associated.

An object of this invention is to provide a tong constructed to enable the same to be 20 used upon pipe and the pipe collars thereof.

Another object of this invention is to provide tongs including a novel locking means adapted for locking the gripping members of the tongs in position to grip either the 25 drill pipe or the collar associated therewith.

Another object of this invention is to provide a tong including a handle, gripping means pivotally secured to the handle, and releasable clip means secured to the handle 30 for holding the operating line securely to said handle.

Other objects and advantages of this invention, it is believed, will be apparent from the following detailed description of a preferred embodiment thereof, as illustrated in 35 the accompanying drawing.

In the drawing:

Figure 1 is a top plan view of the tong embodying this invention, illustrating the 40 tong as secured to a pipe collar shown in end sectional view.

Figure 2 is an enlarged fragmental view of the tong embodying this invention, illustrating the same as secured to a pipe shown 45 in end section.

Figure 3 is an enlarged fragmental view illustrating the clip securing means embodied in this invention.

Figure 4 is an enlarged fragmental view 50 illustrating the lock means embodied in this invention for locking the tong gripping means in position to grip either the pipe or pipe collar.

In the preferred embodiment of this invention, illustrated in the accompanying drawing, 1 indicates a handle which is adapted to be supported in any suitable or desirable manner, as is well understood in the art, by means of a hanger (not shown) secured to the handle preferably at the points 55 2, 3, and 4. The handle 1 is pivotally secured to an arcuate jaw or yoke 5 as by means of a pivot pin 6. A second arcuate jaw 7 is pivoted to the end of the jaw 5 opposite to the pivot 6, the connection between jaws 6 and 7 being constituted by a pivot pin 8. The jaw or yoke 5 and the jaw 7 together 60 substantially form a circle to surround a pipe to be engaged by the tong.

In order to clamp the gripping jaws in 70 position, on the pipe 9 or drill pipe collar 10, the end of the gripping jaw 7 is provided with a pair of lugs 11 and 12, and the inner end of the handle 1 is provided with a complementary lug 13. In clamping the tong on the pipe 9, the lug 13 is engaged behind the lug 12 and the handle 1 pivoted on the pin 6, resulting in the pulling of the end of the 75 jaw 7 inwardly toward the yoke 5 to restrict the circle between the jaw 7 and yoke 5, and thereby clamping the tong on the pipe 9.

In clamping the tong to the pipe collar 10, the lug 13 is engaged behind the lug 11 and the handle rotated on the pin 6, moving the jaw 7 toward the yoke 5 and to a greater degree restricting the substantially circular 80 passage formed between the jaw 7 and yoke 5.

Means are provided for locking the tongs 85 against removal from the pipe 9 or pipe col- 90

lar 10 when the said tongs are in use, which means preferably comprise a keeper 14 which is pivotally secured to the jaw 7 at a pin 15 and provides a pair of shoulders 16 5 and 17 which are adapted to be selectively abutted against a stop the shoulder 18 of the yoke 5 depending upon whether the tongs are used on the pipe 9 or pipe collar 10. This keeper 14 is really a hand-controlled stop for limiting the outward swinging movement of the jaw 7 at two positions, as will presently appear. When used on the pipe 9, the shoulder 16 engages the shoulder 18 and when the tongs are engaged upon the 10 pipe collar 10, the shoulder 17 engages the shoulder 18. Thus, the keeper relatively locks the yoke and jaw in two separate positions. A spring 19 is mounted between the end 20 of the keeper 14 and the end 21 of the 15 jaw 7 in position to normally urge the keeper 14 outwardly. It will be noted that when the keeper 14 is in shoulder-engaged position, the keeper bridges the pivot pin 8 between jaws 5 and 7 and the two shoulders 17 20 and 18 (or 16 and 18) will prevent outward movement of the jaws 5 and 7 relative to each other, thus preventing the jaw 7 from swinging open far enough to permit the pipe 10 to pass laterally out of the tongs. However, since the abutment of the keeper 14 25 and the shoulder 18 only limits the outward movement of the jaws 5 and 7, manipulation of the handle 1 to draw the jaws toward each other will not be affected by the engagement 30 of the keeper and stop shoulder. The yoke 5 is provided with an inserted gripping jaw 22 which is provided with two independent gripping surfaces formed by forming the inner periphery of the jaw 22 of two different 35 radii, as illustrated at 23 and 24, the surface 23 being formed to a curvature to approximately fit the pipe 9 and the surface 24 being formed to a curvature to approximately 40 correspond to the exterior surface of the pipe collar 10. The jaw 7 is also formed to 45 permit the same to grip either the pipe 9 or pipe collar 10 as the same is formed to a diameter on its inner periphery greater than the exterior diameter of either the pipe 9 or pipe collar 10, thereby causing the jaw 7 to 50 be engaged only at a portion of its inner periphery with the pipe 9 or pipe collar 10. A die 231 carried on a pin 241, inserted in the bore 25 formed in the jaw 7, is provided 55 for gripping the pipe 9 or pipe collar 10 and is usually urged into the gripping position by means of a spring 26.

The locking means provided by the keeper 14 is particularly essential to the successful operation of a tong of this type, as when the handle 1 is moved in a direction to tend to disengage the lug 13 from either the lug 11 or 12 to move the tongs into position to permit the same to be actuated by the jerk 60 line 31 to make up or break the pipe 9 or

pipe collar 10, the keeper 14 will operate to hold the tong in position on the pipe 9 or pipe collar 10 until the jerk line has again operated to cause the tongs to grip the casing or drill stem. 70

In order to clamp the tong on the pipe 9 or pipe collar 10, the handle 1 is provided with a gripping handle 32 which is provided with a guard 33 and the keeper 14 is provided with a handle 34 and the operator gripping the handles 32 and 34 may swing the tong around the pipe or pipe collar and again actuate the handle 34 to the position to cause the same to lock the jaw 7 in the proper position to grip either the pipe or 80 pipe collar. 75

In order to permit the jerk line 31 to be removably secured to the handle 1 and not be secured in position in a manner to prevent the same being accidentally disengaged, a 85 clip 35 is provided which acts to close the hook 36 formed at the end of the handle 1 within which the jerk line 31 is secured. The clip 35 is secured at a pivot pin 37 to the handle 1 and is yieldably urged in position 90 to close the hook 36 by means of a spring 38. The clip 35 has one end positioned inside of the tip of the hook so that the spring 38 yieldingly urges the clip into engagement with said tip. 95

Formed on the opposite sides of the handle 1 are eyes 39 and 40 into which a dead line 41 or the like from an automatic actuating mechanism may be secured to rotate the tong on the pipe 9 or pipe collar 10. The eyes 39 and 40 are provided on the opposite sides of the handle 1 in order to permit the line 41 to be secured to either of said eyes, depending upon the position of the tongs as the tongs are inverted in use when they are 100 employed for the alternate purposes of making up and breaking the string of casing or drill stem. 105

It will be noted from the examination of Figures 1 and 2 that when the keeper 14 is 110 in the position indicated in Figure 1, the spring 19 will operate to hold the jaw 7 in such position that the lug 11 will be held in the path of the actuating lug or dog 13 formed on the head of the tong handle or 115 lever 1, and when the keeper is held in the position indicated in Figure 2, the spring 19 will operate to hold the lug 12 in the path of the actuating dog or lug 13. Of course when the lever is actuated, the spring 19 120 yields and permits the jaw 7 to move inwardly to come against the clamped part. 125

Having fully described my invention, it is to be understood that I do not wish to be limited to the details of construction herein set forth, which are susceptible to modification without departing from the scope of my invention as defined in the appended claims.

I claim:

1. In a tong to engage pipes and collars 130

of different diameters, the combination of a handle in the form of an operating lever for the tong, a yoke pivotally attached to the head of the lever and extending partially 5 around the circumference of the pipe or collar to be clamped, a clamping jaw pivotally secured to the end of the yoke remote from the lever, a hand-operated stop pivotally attached to the jaw and having means for 10 engaging the yoke to hold the clamping jaw in two different positions with respect to the axis of the pipe, to receive a relatively small or a relatively larger pipe, and means on the head of the operating lever for engaging the 15 end of the said jaw in either of the said positions to clamp the pipe or collar between the jaw and the yoke.

2. In a tong to engage pipes and collars of different diameters, the combination of a 20 handle in the form of an operating lever for the tong, a yoke pivotally attached to the head of the lever and extending partially around the circumference of the pipe or collar to be clamped, a clamping jaw pivotally secured 25 to the end of the yoke remote from the lever, a hand-operated stop pivotally attached to the jaw and having means for engaging the yoke to hold the clamping jaw in two different positions with respect to the axis of the 30 pipe, to receive a relatively small or a relatively larger pipe, a spring between the hand-operated stop and the jaw urging the jaw in an outward direction, and means on the head of the operating lever for engaging the 35 end of the said jaw in either of the said positions to clamp the pipe or collar between the jaw and the yoke.

3. In a tong to engage pipes and collars of different diameters, the combination of a 40 handle in the form of an operating lever for the tong, a yoke pivotally attached to the head of the lever and extending partially around the circumference of the pipe or collar to be clamped, a clamping jaw pivotally secured to the end of the yoke remote from the lever, a hand-operated stop lever pivotally attached to the jaw near its pivotal connection to the yoke, said stop lever and said 45 yoke having means cooperating to enable the stop lever to be set in two different positions operating to hold the said jaw in two different positions with respect to the axis of the pipe to enable the tong to receive a relatively small or a relatively larger pipe or collar, and means on the head of the operating lever for engaging the end of the said jaw in either of the said positions of the same to clamp the pipe or collar between the jaw and 50 the yoke.

4. In a tong to engage pipes and collars of different diameters, the combination of a handle in the form of an operating lever for the tong, a yoke pivotally attached to the 55 head of the lever and extending partially

around the circumference of the pipe or collar to be clamped, a clamping jaw pivotally secured to the end of the yoke remote from the lever, a hand-operated stop lever pivotally attached to the jaw adjacent the pivotal connection of the yoke for engaging the yoke to hold the clamping jaw in two different positions with respect to the axis of the pipe, and corresponding to a relatively small or a relatively larger pipe, said operating lever having an actuating dog for engaging the free end of the jaw, and the free end of said jaw having two lugs to engage the actuating dog, one of which is in the path of the dog when the jaw is held in the position corresponding to a smaller pipe, and the other of which is held in the path of the actuating dog when the jaw is in the position corresponding to a larger pipe.

5. In a tong to engage pipes and collars of different diameters, the combination of a handle in the form of an operating lever for the tong, a yoke pivotally attached to the head of the lever and extending partially around the circumference of the pipe or collar to be clamped, a clamping jaw pivotally secured to the end of the yoke remote from the lever, a hand-operated stop lever pivotally attached to the jaw adjacent the pivotal connection of the yoke for engaging the yoke to hold the clamping jaw in two different positions with respect to the axis of the pipe, and corresponding to a relatively small or a relatively larger pipe, said operating lever having an actuating dog for engaging the free end of the jaw, and the free end of said jaw having two lugs to engage the actuating dog, one of which is in the path of the dog when the jaw is held in the position corresponding to a smaller pipe, and the other of which is held in the path of the actuating dog when the jaw is in the position corresponding to a larger pipe.

6. A tong including a handle, a yoke pivotally secured to the handle, a gripping jaw pivotally secured to the yoke, a latch member pivotally secured to the gripping jaw and providing a pair of shoulders, a shoulder formed on the yoke, and the shoulders of said latch member being adapted to be alternately engaged with the shoulder of said yoke to determine the position of the gripping jaw.

7. In a pipe tong, a handle having associated therewith a plurality of arcuate pipe gripping jaws substantially forming a circle around a pipe to be engaged thereby, pivot means interconnecting adjacent jaws for inward movement relative to each other to

reduce the circle and for outward movement relative to each other to open the circle, a stop formed upon the exterior face of one jaw, a keeper comprising a bar pivoted to the exterior face of the adjacent jaw and extending across said pivot interconnecting said jaws for movement in a plane at right angles to the axis of said circle, a spring normally urging said bar toward the face of 10 said adjacent jaw to abut the said stop for limiting outward movement of the jaws to prevent opening of the circle sufficient for the pipe to pass laterally out of the tong.

Signed at Los Angeles, California, this
15 22nd day of Nov. 1927.
